(57) **CLAIM**

The ornamental design for a vehicle, as shown and described.

DESCRIPTION

FIG. 1 is an isometric view of a top, front, and left side of an ornamental design for a vehicle;

FIG. 2 is an isometric view of a top, rear, and left side of the vehicle of FIG. 1;

FIG. 3 is a front elevational view of the vehicle of FIG. 1; FIG. 4 is a rear elevational view of the vehicle of FIG. 1; FIG. 5 is a left side elevational view of the vehicle of FIG. 1;

FIG. 6 is a top plan view of the vehicle of FIG. 1; and, FIG. 7 is a bottom plan view of the vehicle of FIG. 1. The broken lines are included for the purpose of illustrating unclaimed portions of the vehicle and form no part of the claimed design.

1 Claim, 7 Drawing Sheets
